(57) **CLAIM**

The ornamental design for a guitar string, as shown and described.

DESCRIPTION

FIG. 1 is a prospective view of a guitar string showing the first embodiment of my new design;

FIG. 2 is a front view of the guitar string of FIG. 1;

FIG. 3 is a back view of the guitar string of FIG. 1;

FIG. 4 is a side view of the guitar string of FIG. 1;

FIG. 5 is another side view of the guitar string of FIG. 1;

FIG. 6 is a top view of the guitar string of FIG. 1;

FIG. 7 is a bottom view of the guitar string of FIG. 1;

FIG. 8 is another front view of the guitar string of FIG. 1;

FIG. 9 is an enlarged detail view of the guitar string taken at line-9 of FIG. 8;

FIG. 10 is a perspective view of a guitar string showing the second embodiment of my new design;

FIG. 11 is a front view of the guitar string of FIG. 10;

FIG. 12 is a back view of the guitar string of FIG. 10;

FIG. 13 is a side view of the guitar string of FIG. 10;

FIG. 14 is another side view of the guitar string of FIG. 10;

FIG. 15 is a top view of the guitar string of FIG. 10;

FIG. 16 is a bottom view of the guitar string of FIG. 10;

FIG. 17 is another front view of the guitar string of FIG. 10; and,

FIG. 18 is an enlarged detail view of the guitar string taken at line-18 in FIG. 17.

The broken lines illustrate the portions of the guitar string that form no part of the claimed design.
